UNITED STATES PATENT OFFICE.

MERL J. HARKLESS, OF HOMEWOOD, ILLINOIS.

CIGARETTE LIGHTER.

Application filed September 13, 1926. Serial No. 134,959.

This invention relates to cigar and cigarette lighters in general and more particularly to such lighters as are employed under conditions wherein difficulty is apt to be experienced in touching the cigarette to the lighter or holding it there until lighted. Such conditions for example, are present in connection with the cigarette lighters used on automobiles where the necessity for paying attention to driving, the vibration of the car etc. make it difficult at times to either touch the cigarette to the lighter or hold it there until lighted.

It is accordingly an object of this invention to provide in connection with the cigarette lighter means for holding the cigarette in proximity to the lighter until lighted.

It is further an object of this invention to provide in connection with a cigarette lighter means for guiding the cigarette to the lighter without danger of burning the fingers and without materially distracting the attention from other things.

It is also an object of this invention to provide in connection with the cigar and cigarette lighter, cigarette holding and guiding means for facilitating the lighting of the cigarette, which means may be readily moved to inoperative position to permit access to the lighter for the purpose of lighting a cigar which might be too large to be accommodated by the holder.

It is also an object of this invention to provide an attachment for readily providing certain forms of cigarette and cigar lighters now in use with the aforementioned means.

Other and further objects of this invention will be apparent as the same becomes better understood by referring to the specification and claims when taken in connection with the accompanying drawings, wherein

Fig. 1 is a plan view partly in section of a cigar or cigarette lighter embodying this invention; and

Fig. 2 is an elevational view of the same.

Referring to the drawings more particularly, numeral 1 represents the body of the cigar lighter of the usual type which may be of cylindrical shape having a reduced portion 2 at one end thereof which is threaded and secured to the dash or other suitable place 3 of an automobile by means of nuts

4, one on either side of said dash. Although this invention is illustrated in connection with cigar lighters of the type usually used on automobiles, it is to be understood that this invention may also be used in connection with other types of cigarette lighters. The other end of the mount or body 1 is provided with a curled flange 5 surrounding an opening 6 in said end, which opening affords access to a filament 7 operatively mounted in said body adjacent said opening. A U-shaped spring clip 8 is removably secured on the body 1 inwardly of the curled flange 5 and has hinged thereon at a point equidistant from its ends a diametrical bar 9. The bar 9 extends outwardly and across the end of the body 1 and is provided with a spring latch 10 adapted to removably grip the edge of the said body over the flange 5. A cylindrical cigarette holder or cigarette guide 11 is mounted on the bar 9, extends outwardly therefrom and has its base adjacent the filament 7 so that a cigarette positioned in such holder may be lit by said filament. A funnel portion 12 is provided on the outer end of the holder 11 to facilitate entrance thereto of a cigarette. A cigarette 13 is illustrated in dotted lines.

It will be noted that a person driving a car or otherwise engaged in an occupation requiring close attention thereto, may very easily find the entrance to the cigarette lighter and in his search for such entrance will not be apt to burn his fingers because of the remoteness of the funnel shaped portion 12 from the filament 7 of the lighter, as well as the fact that when the holder 11 is in operative position it is practically impossible to touch the filament without removing the holder.

It will further be apparent that the necessity for holding the cigarette up to the filament after the entrance thereto has been found is eliminated by the use of the holder. In case it is desired to light a cigar which is too large for the holder, the latch 10 may be released permitting the holder to be swung out from in front of the filament.

By use of the spring clip 8 in connection with the holder, the ordinary forms of cigar lighters may be readily converted so as to provide the advantages of my invention.

I am aware that many changes may be

made and many details varied throughout a wide range without departing from the principles of this invention and I therefore do not wish to be limited to the details shown or described.

I claim:

1. A lighter of the character described comprising a mount, an ignition element operatively disposed thereon, and a cigarette guide or holder hinged to said mount and adapted when in operative position to cooperate with said element to facilitate lighting of a cigarette thereby and when in inoperative position to permit access to said element for lighting a cigar.
2. The combination with a lighter of the character described including a mount and ignition element thereon, of a cigarette guide or holder having a spring clip associated therewith adapted to be removably connected to said mount for holding the inner end of said guide adjacent said element.
3. The combination with a lighter of the character described including a mount and ignition element thereon, of a cigarette guide or holder having a spring clip associated therewith adapted to be removably connected to said mount for holding the inner end of

said guide adjacent said element, the guide being hinged to said clip.

4. A lighter of the character described comprising a mount, an ignition element operatively disposed thereon, a cigarette guide or holder detachably connected to said mount and adapted to cooperate with said element to facilitate the lighting of a cigarette thereby, and hinge means for permitting the temporary removal of said guide from operative to inoperative position without completely detaching the guide from the mount when it is desired to light a cigar.

5. A lighter of the character described comprising a mount, an ignition element operatively disposed thereon, a cigarette guide or holder connected to said mount and adapted to cooperate with said element to facilitate the lighting of a cigarette thereby, and means for permitting the temporary removal of said guide from operative to inoperative position without completely detaching the guide from the mount when it is desired to light a cigar.

In witness of the foregoing I affix my signature.

MERL J. HARKLESS.
